DESIGN FOR A TEXTILE FABRIC OR SIMILAR ARTICLE

Robert Scheiwiller, Union City, N. J., assignor to Ellen Lace & Embroidery Co., Inc., New York,
N. Y., a corporation of New York

Application August 5, 1938, Serial No. 79,113

Term of patent 3½ years

To all whom it may concern:

Be it known that I, Robert Scheiwiller, a citizen of the United States, residing in Union City, Hudson County, New Jersey, have invented a new, original, and ornamental Design for a Textile Fabric or Similar Article, of which the following is a specification, reference being had to the accompanying drawing, forming part thereof.

In the drawing, the figure is a plan view of a textile fabric or similar article showing my new design.

The fabric of my design consists of yarn superimposed upon a sheer background.

I claim:

The ornamental design for a textile fabric or similar article, substantially as shown and described.

ROBERT SCHEIWILLER.
